ELECTROMAGNETIC TRIP DEVICE

Ture Lindstrom, Edgewood, Jerome Sandin, Forest Hills, and Herbert L. Rawlins, Pittsburgh, Pa., assignors to Westinghouse Electric Corporation, East Pittsburgh, Pa., a corporation of Pennsylvania

Application November 19, 1945, Serial No. 629,662

9 Claims. (Cl. 175—372)

1

This invention relates to circuit breakers, and more particularly, to overload trip devices for controlling the automatic operation of circuit breakers.

One object of the invention is to provide a circuit breaker embodying an improved trip device which is of simple construction, reliable in operation and inexpensive to manufacture.

Another object of the invention is to provide a circuit breaker embodying a novel trip device operable to trip the breaker after a relatively long time delay in response to overload currents of relatively low value, after a relatively short time delay in response to overload currents of intermediate value up to a predetermined value and instantaneously in response to overloads above said predetermined value.

Another object of the invention is to provide a circuit breaker embodying a novel trip device having a plurality of time delay devices one of which controls the trip device to trip the breaker in response to relatively high overload currents, and another of which time delay devices controls the trip device to trip the breaker in response to relatively low overload currents.

Another object of the invention is to provide a circuit breaker embodying a novel trip device according to the preceding paragraph wherein one of the time delay devices comprises a sealed casing movable to trip the breaker and containing a body of liquid, said casing having a core member disposed therein and movable relatively thereto to control the tripping movement of said casing, and another of said time delay devices comprises a mechanical escapement for controlling the movement of the casing.

The novel features that are considered characteristic of this invention are set forth in particular in the appended claims. The invention itself, however, both as to structure and operation together with additional objects and advantages thereof, will be best understood from the following detailed description of one embodiment thereof when read in conjunction with the accompanying drawings, in which:

Figure 1 is a side-elevational view, partly in section, of a circuit breaker embodying the invention.

Fig. 2 is an enlarged sectional view of the trip device taken substantially on line II—II of Fig. 3 and looking in the direction of the arrows.

Fig. 3 is a bottom view of the trip device.

Fig. 4 is a detail view showing the escapement ratchet wheel and the inertia device,

Fig. 5 is a skeletonized view showing the fixed

2

and movable core members and armatures in their relative positions but omitting the springs and sealed casing to more clearly illustrate the air gaps in the magnetic circuit, and

5 Fig. 6 is a detail vertical view taken on line VI—VI in Fig. 2 and showing the calibrating spring toggle.

Referring to Figure 1 of the drawings, the reference numeral 11 designates a base of strong insulating material which supports the various parts of the circuit breaker. A pair of terminals 13 and 15 are suitably secured to the base and each terminal has one or more connecting studs 19 which extend through the back of the base 11 and serve to electrically connect the breaker to the circuit which it controls.

The upper terminal 13 has a contact block 21 of rigid conducting material secured thereto; and a rigid contact block 23 secured to the base is electrically connected to the lower terminal 15 through the energizing winding of the trip device of the breaker, which will be hereinafter described.

25 The contact means and mechanism of the circuit breaker illustrated are similar to the circuit breaker fully disclosed in Patent No. 2,214,471 issued September 10, 1940, to Leon R. Ludwig and Merle E. Horn, and assigned to the assignee of the present invention. Hence only a brief description of these parts will be given in this application.

30 The main stationary contacts 25 and 27 are rigidly secured to the contact blocks 21 and 23, respectively; and the auxiliary stationary contacts 29 and 31 are secured to a triangularly-shaped contact platform 33 of conducting material which is mounted on the upper portion of the block 21 for limited tilting and rocking movement by means of pins 35 projecting from the opposite sides of the platform which engage in slots 37 provided in a pair of side walls 39 secured to the block 21. The platform 33 is biased outwardly from the base 11 by a plurality of springs 41 and 43, and outward movement of the platform 35 is limited by the engagement of the pins 35 with the outer ends of the slots 37 and by stop projections 45 carried by the platform adjacent its upper end. The platform 33 and, consequently, the auxiliary contacts 29 and 31 are electrically connected to the terminal 13 by means of a flexible shunt conductor 47.

35 The movable contact means of the circuit breaker comprises a channel-shaped contact arm 49 of conducting material which is rigidly secured to a pivoted switch member 51 by means of a plu-

rality of screws 53. The contact arm 49 carries a main contact bridging member 55 for bridging the main contacts 25 and 27, and an auxiliary contact member 57 for engaging the stationary auxiliary contacts 29 and 31, the auxiliary contact member 57 being secured to the upper end of the channel-shaped contact arm 49 by a plurality of screws 59.

The main contact bridging member 55 is formed of rigid conducting material, and is loosely mounted on the contact arm 49 for limited movement relative to the contact arm toward and away from the main contacts 25 and 27 by means of a pair of studs 61 secured to the contact carrying arm 49, only one stud being shown. A pair of coil springs (not shown) encircle the studs 61, and are disposed between the contact carrying arm 49 and the bridging member 55 for biasing the bridging member toward the stationary main contacts 25 and 27 with a predetermined force. The ends of the bridging member 55 are beveled to lie parallel with the beveled edges of the contact blocks 21 and 23, and have a pair of contacts 67 secured thereto for engaging the main stationary contacts 25 and 27.

The auxiliary contact member 57 is formed of rigid conducting material, and has an intermediate contact 69 and an arcing contact 71 secured thereto for engaging the intermediate and arcing contacts 29 and 31 of the stationary contact means.

A flexible shunt conductor 73 electrically connects the auxiliary contact arm 49 to the main stationary contact block 23. The flexible conductor 73 has its upper end secured to the contact arm 49 by the lower bolts 53. The lower end of the flexible shunt conductor 73 is secured to the lower contact block 23 by means of a bolt 71.

The switch member 51 has a yoke-shaped lower end which is pivotally mounted between the side walls of a main frame 79 by means of the pivot pin 81. The switch member 51 is movable about its pivot axis to open and closed circuit positions to open and close the contact means of the breaker by means of an operating mechanism indicated generally at 83.

The operating mechanism 83 is supported by the main frame 79 and comprises an actuating lever 85 pivoted on a pin 87 carried by the frame, and is connected to the switch member 51 by a link 89. An operating member 91 is also pivoted on the pin 87 for movement about the same axis as the actuating lever 85. The actuating lever 85 is normally and releasably connected to the operating member 91 for movement thereby by means of a pair of latches 93 and 95, which are pivotally mounted on the lever 85 at 97 and 99, respectively. The latch 93 engages a roller 101 carried by the operating member 91, and this latch is, in turn, held in latching position by the auxiliary latch 95. The operating member 91 is adapted to be releasably held in closed circuit position by means of a main holding latch 103 pivoted at 119, which releasably engages the roller 101. The auxiliary latch 95 is provided with a curved tailpiece 105 by means of which it is released to cause release of the latch 93 and consequent tripping of the circuit breaker by the release of the actuating lever 85 from its connection with the operating member 91. When released the actuating member 85 moves in a counterclockwise direction about the pivot axis 87, causing opening of the movable contact means. During this movement, a cam surface

107 of the lever 85 engages the rounded nose of the main holding latch 103, moving the holding latch to released position to effect release of the operating member 91. The switch member 51 and the actuating lever 85 are biased to open position by means of a pair of accelerating springs 109 (only one being shown), which are connected at their upper ends to the switch member 51 and at their lower ends to the sides of the main frame 79.

To close the circuit breaker after it has been tripped open, the operating member 91 is first moved in a counterclockwise direction about the pivot axis 87 to the open position to effect resetting of the latches and reestablishment of the releasable connection between the actuating lever 85 and the operating member 91. After the connection is thus established, the operating member 91 is moved in a clockwise direction to closed position by means of a handle 111 to effect closing of the contact means of the breaker. The clockwise or closing movement of the operating member 91 is limited by a portion 92 thereof striking a fixed stop 94 on the frame 79. When the parts have been moved to closed position, the main holding latch 103 reengages the roller 101 to hold the operating member in closed position. The stop 94 is located to permit a slight overtravel of the member 91 to insure proper engagement of the latch 103 with the roller 101. It will be noted that the construction of the operating mechanism is such that the movable contact means is trip-free of the operating member 91; that is, when the breaker is tripped, the contact means move to open position irrespective of the position of the operating member 91.

The mounting arrangement of the contact means is such that during opening of the breaker the main bridging member 55 is first separated from the stationary contacts 25 and 27, while the auxiliary contacts remain in engagement by reason of the outward movement of the contact platform 33 under the influence of the biasing springs 41 and 43. After the bridging member 55 has separated a predetermined distance from the main stationary contacts, the intermediate contacts 29 and 69 begin to separate. This takes place as soon as the pins 35 engage the ends of the slots 37. During this time, the arcing contacts 31 and 71 remain in engagement due to the rocking movement of the contact platform 33. After the intermediate contacts have separated a predetermined distance, the arcing contacts 31 and 71 begin to separate. During closing, the contacts engage in the reverse order, as will readily be understood. It will thus be seen that the arc formed during separation of the contacts is drawn only between the arcing contacts 31 and 71.

The circuit breaker is adapted to be tripped open either manually, or automatically, in response to predetermined overload conditions in the circuit, by means of a trip device indicated generally at 115.

The trip device comprises a trip lever 117 which is pivotally mounted intermediate its ends on the frame 79 by means of a pivot pin 119, and an electromagnetic trip means, indicated generally at 121, which is operable in response to the predetermined overload conditions to move the trip lever 117 to tripping position to cause automatic opening of the circuit breaker.

One arm 123 of the trip lever 117 is offset and extends inwardly toward the base 11 of the circuit breaker, and has its inner end disposed imme-

diate above the tripping electromagnet 121 to be engaged and moved by a plunger of the electromagnet to effect automatic tripping of the breaker. The arm 123 of the trip lever is provided with a projection 125 which is adapted to engage the curved tailpiece 105 of the auxiliary latch 95 to move this latch to released position upon movement of the trip lever to tripping position. The other arm of the trip lever 117 forms a handle 127 whereby the trip lever may be manually moved to tripping position to effect manual opening of the circuit breaker. A spring 129 connects the arm 123 of the trip lever 117 to an extension of the main holding latch 103 so that the spring thus serves to bias the main holding latch to latching position and the trip lever to its normal inoperative position, as shown in Fig. 1.

The electromagnet 121 comprises a stationary core member 131, a movable core structure indicated generally at 133, a trip rod 135 operable thereby, and an energizing winding 137 having one end connected to the contact block 23 and the other end connected to the terminal 15.

The fixed core member or magnet yoke 131 is generally U-shaped and is provided with mounting feet 139 by means of which the trip device is rigidly supported on the base 11, being secured to the base by means of bolts 141. The contact block 23 is electrically connected to the winding 137 by means of a conductor 143. The lower stud 19 is formed at right angles and secured to the front of the base and to the terminal 15 by means of a bolt 145 and nut 147. The winding 137 is insulated from the lower leg of the magnet yoke 131 and from the movable core structure 133 by means of an insulating spool 149.

The movable core structure 133 comprises a sealed casing 151 (Fig. 2) of non-magnetic material having a portion 153 of reduced diameter at its lower end and having an armature 155 secured to the bottom of the reduced portion. The armature 155 is secured to the casing 151 by means of a portion of the bottom of the casing extending through an opening in the central portion of the armature and being riveted over against the inside of the armature as at 157. The upper end of the casing 151 is closed by means of a flanged disc 159 the flange of which is brazed or soldered to the inner surface of the casing. The central portion of the disc 159 is provided with an integral inwardly extending tube 161 for the purpose of filling the casing with a suitable liquid to the proper level, there being a space in the upper end of the tube which may be filled with a suitable gas. After the fluid is placed in the casing a screw 163 is inserted tightly into the tube 161 and brazed therein thus hermetically sealing the casing 151.

Disposed within the sealed casing 151 is a core member 165 of magnetic material which is biased upwardly by means of a spring 167 against the filler tube 161 which acts as a stop therefor. The spring 167 is compressed between a shoulder formed in the casing 151 by the reduced portion 153 thereof and a shoulder formed by the enlarged upper end 169 of the core member 165. The core member 165 is cylindrical in form and the enlarged upper end 169 has a triangular cross section the apex of which is disposed substantially on a line with the apex of a cylindrical bushing 171 of magnetic material having its outer periphery tapered substantially, as shown in Fig. 2. The bushing 171 threadedly engages an opening in the upper leg of the magnet yoke 131 and a similar bushing 173 also of magnetic material is screwed

into an opening in the lower leg of the magnet yoke. The bushings 171 and 173 are provided with guide rings 174 of non-magnetic material to guide the sealed casing 151 in its vertical reciprocal movement. The bushings 171 and 173 also form a part of the magnetic circuit as will be hereinafter more fully brought out.

Extending axially through the core member 165 is a passage 175 in which is disposed a ball check valve 177 loosely held in position by means of a pin 179. Two other passages 181 and 183 extend radially through the wall of the core member 165 to permit fluid to bypass the check valve 177, the passage 183 having a restricted portion for controlling the rate of flow of the fluid from one side of the core member 165 to the other.

Welded or otherwise suitably secured to a shouldered portion of the sealed casing 151 is a cylinder 185 of non-magnetic material the periphery of which is of the same diameter as the periphery of the enlarged portion of the casing 151. The cylinder 185 has secured to the lower end thereof an inwardly flanged collar 187 which normally rests upon a stop member 189 supported on a screw stud 191 threadedly engaging a tapped opening in the lower leg of the magnet yoke 131 and spaced therefrom by a spacer 192. The stop 189 serves to support the cylinder 185 and the sealed casing 151 in a normal fixed position with relation to the energizing winding 137 and the fixed magnet yoke 131.

The flange on the collar 187 extends inwardly an extent sufficient to engage and support a cylindrical armature 193 which extends in nested relation in the cylindrical space between the reduced portion 153 of the sealed casing 151 and the cylinder 185. The armature 193 is biased downwardly away from the sealed casing 151 and against the flange of the collar 187 by means of a spring 195 compressed between the bottom of the armature 155 and an adjustable spring seat 197 which is supported on a threaded plug 199 screwed into a tapped opening in the lower end of the armature 193. The plug 199 is provided with a screw driver slot across its bottom surface whereby it is rotatable in the threaded opening in the armature 193 to move the spring seat 197 up and down to thereby adjust the tension of the spring the purpose of which adjustment will be fully set forth hereinafter. The plug 199 is provided with a groove extending diametrically across its upper side which is engaged by a projection 201 which may, for conveniences, comprise a rod welded to the under side of the spring seat 197.

When the plug 199 is rotated in either direction the rod 201 is forced upwardly and when the plug has rotated 180° the rod is forced back into the groove by the force of the spring 195. The spring seat 197 is prevented from rotating during this adjustment by an end thereof extending into a slot 203 in the wall of the armature 193.

As will be fully described hereinafter in the description of the operation of the trip device, the core member 165 and the control of the passage of fluid past the core member provides a long time delay when the device is operated in response to overload currents of relatively low value of, for instance, up to 300% of normal rated current. Means is also provided whereby a relatively short time delay is effected when the device is operated in response to overload currents in an intermediate range, for example, between

300% and 1000% of normal rated current. This means comprises a mechanical escapement device indicated generally at 205.

Referring to Figs. 2 and 3, integral with the armature 193 and extending downwardly therefrom (Fig. 2) is a pair of spaced projections 207 which between them carry a pin 209. The pin 209 is engaged by open slots 211 in a pair of spaced arms 213 forming one arm of a lever 215 pivoted on a fixed pivot pin 217 supported in the side walls 219 of a frame 221. A roller 220 is mounted on a pin 222 supported between the arms 213 for cooperation with the collar 187 as will be fully described later. The frame 221 is suitably supported on the lower leg of the magnet yoke 131 by means of the screw stud 191 and a pair of screws 223 (only one being shown).

The other arm of the lever 215 comprises a mass 225 having a projection 227 integral therewith and extending laterally therefrom to which is connected one end of a spring 229 having its other end connected to one arm 231 of a segmental lever 233 pivotally mounted on the pivot pin 217. The spring 229 is given an initial tension which is maintained by a spacer rod 235 disposed within the coil of the spring 229 and extending between the end of the arm 231 of the lever 233 and the end of an adjusting screw 236 adjustably mounted in the projection 227 of the arm 225 of the lever 215.

The other arm of the lever 233 comprises a segment gear 237 which meshes with a pinion 239 mounted for rotation on a shaft 241 supported in the side walls 219 of the frame. The pinion 239 is secured to one end of a sleeve 243 surrounding the shaft 241 and having its other end secured to an escapement ratchet wheel 245. An inertia member 247 mounted on a shaft 249 cooperates with the teeth on the periphery of the ratchet wheel 245 and has a mass 251 secured thereto by means of rivets 253 only one of which is shown.

The lever 215 (Fig. 2) is biased against clockwise movement by means of a calibrating spring 255 having its upper end hooked over a movable stud 257 slidable vertically in a slot in the magnet yoke 131 and in a corresponding slot in a scale plate 259. The scale plate 259 is suitably secured to the magnet yoke as by screws (not shown). The stud 257 is clamped to the scale plate in its adjusted position by a thumb nut 261. The scale plate 259 is provided with a suitable scale (not shown) arranged vertically adjacent the path of movement of the stud 257 and a pointer (also not shown) is provided movable with the stud 257 and thumb nut 261 which cooperates with the scale to indicate the setting to which the device is adjusted.

The lower end of the spring 255 is hooked over the knee pin 263 of a toggle comprising toggle links 265 and 267, the toggle being disposed in a cut-out portion of the mass 225. The toggle link 265 is mounted on a fixed pivot 269 supported in the side walls 219 of the frame 221 and the toggle link 267 is connected to the lever 215 by means of a pin 271. The knee end of each of the toggle links 265 and 267 is bifurcated and the end of the link 265 extends between other forks of the link 267. The lower end of the spring 255 is hooked around the knee pin 263 between the forks of the link 265 and the forks of the toggle link 267 extend beyond the knee pin where they engage the ends of a pin 273 in the link 265 to maintain the toggle 265—267 slightly underset below a line

drawn through the centers of the pins 269 and 271.

The trip drive functions within two ranges of overload currents below a predetermined value to trip the breaker after a relatively long time delay in the lower range of overload currents, with a relatively short time delay in the intermediate range of overload currents and instantaneously in response to overload currents above the predetermined value, or on short circuits. These ranges of overload currents may be arbitrarily defined as up to 300% of normal rated current for the low range, 300% to 1000% of rated current for the intermediate range, and 1000% or more of rated current for the instantaneous tripping range. The limits of the intermediate range of overloads set forth are to be considered merely by way of example and these may be varied considerably to suit particular requirements. For instance, by the provision of stronger or weaker springs entirely different sets of values may be established.

There are three main air gaps in the magnetic circuit indicated at A, B and C, which are more clearly shown in Fig. 5. It will be observed that the lower sharp edge of the bushing 171 which forms a part of the magnetic circuit and the upper edge of the enlarged portion 169 of the core member 165 which forms the air gap A lie in substantially the same horizontal plane, when these parts are in their normal positions with the core member against the stop 161. These edges are shaped to produce an extremely high magnetic flux density in the air gap A. The air gap B comprises two magnetic circuits b1 and b2 (Fig. 5). The air gap B produces the tripping force for long time delay tripping in response to overload currents in the low range of overload currents up to approximately 500% of normal rated current.

When a persistent overload occurs in the low range of overload current values, for instance, 150% of normal current, the magnetic circuit is energized but, due to the extreme high density flux across the air gap A, the core member 165 will be held in substantially the position shown in Figs. 2 and 5 while the magnetic flux in the air gap B starts to move the armatures 155 and 193 upwardly. At this current value, the upward pull of the armature 193, through the spring 195 is added to the upward pull of the armature 155. This pull of the armature 193 is insufficient to further compress the spring 195, consequently these armatures cause a slow upward movement of the sealed casing 151 forcing fluid to flow from below the core member 165 through the orifice 183 to the chamber above the core member. As this movement of the armatures 155 and 193 and the sealed casing 151 continues, the air gap B is gradually reduced thereby providing a greater pull on the sealed casing at the time the casing engages the trip mechanism to effect the actual tripping of the breaker. As soon as the sealed casing starts its upward movement the pressure of the fluid below the core member 165 causes the ball check valve 177 to close forcing the fluid through the restricted passage 183 thus providing a relatively long time delay on overload currents within the low range of values. During long time delay tripping operations, the previously described escapement device 205 is operated but since the operation is slow the escapement device offers relatively little resistance to the tripping operation.

Before the sealed casing can start its upward tripping movement, it is necessary that the forces

in the magnetic circuit be great enough to overcome the tension of the calibrating spring 255. When the forces are sufficient to overcome the spring 255 the movable core structure, acting through the pin 209 and the arm 213, rotates the lever 215 clockwise about its pivot 217. This action causes collapse of the toggle 265-267 and reduces the effective force of the spring 255 resisting operation of the lever 215.

After the circuit is opened by opening of the breaker contacts and the winding 137 is deenergized, the movable core structure 133 is returned to its normal position against the stop 189 by gravity aided by the spring 255. The spring 167 at the same time causes opening of the check valve 177 permitting a free flow of fluid to the space below the core member 165 and restores the core member upwardly to its normal position against the stop 161.

The operation of the device is somewhat different on overload currents in the intermediate range, that is, between 300% and 1000% of normal current. When the winding 137 is energized by an overload current in the intermediate range, of, for instance, 800% of normal current, the armature 193 is attracted with sufficient force to overcome the spring 195 and quickly close the air gap b1 (Fig. 5). This would result in substantially instantaneous tripping if the armature 193 were not otherwise restrained. It is desirable that the time delay on intermediate overloads be much shorter than on overloads in the low range of values but greater than the instantaneous tripping. To this end the armature 193 is restrained by the mechanical escapement device 205. When the armature 193 starts to move upwardly it acts through the pin 209 to rotate the lever 215 in a clockwise direction. The lever 215 through the spring 229 (Fig. 1) rotates the segmental lever 233 which, in turn, rotates the pinion 239 and the ratchet wheel 245 (Figs. 2 and 4) in a counterclockwise direction under the control of the inertia member 247 which retards the upward movement of the armature 193.

The pull of the armature 155 in response to overloads in the intermediate range is not great enough to displace the core member 165 relative to the fixed core member, consequently the core member, in the absence of other forces, would remain substantially stationary while the sealed casing 151 moved very slowly in tripping direction being retarded by the flow of fluid through the orifice 183. This would provide a relatively long time delay in response to overload currents in the intermediate range. In order to provide short time delay tripping in the intermediate range of overload currents, other means are provided to actuate the sealed casing in tripping direction. This means comprises the lever 215 and the roller 220. When the lever 215 is rotated in a clockwise direction by upward movement of the armature 193, the roller 220 engages the collar 187 and moves the tube 151 upwardly therewith. It will be observed that the roller 220 is disposed on the arm 213 at approximately one-half the distance from fulcrum 217 as the pin 209, consequently the armature 193, acting through the pin 209, lever 215 and the roller 220 applies twice the force to move the tube than is applied directly by the armature and moves the tube at approximately one-half the speed of the armature 193. This provides for gradual closing of the air gap b1 and insures that the device will not function to trip the breaker until the ratchet wheel 245 escapes the inertia member 247.

The ratchet wheel 245 is provided with teeth about a portion of its periphery as can be clearly seen in Figs. 2 and 4 of the drawings. As viewed in Figs. 2 and 4, the ratchet wheel is rotated in a counterclockwise direction and the duration of the short time delay tripping in response to overloads in the intermediate range is measured by the time required for the last tooth on the ratchet wheel to escape the inertia member 247.

The time at which the armature 193 will start to move upwardly in tripping direction in response to overload currents in the intermediate range may be varied by varying the tension of the spring 195. This is accomplished by rotating the threaded plug 199 (Fig. 2) to increase or decrease the compression of the spring 195.

The duration of the short time delay tripping may be varied by changing the position of the ratchet wheel 245 relative to the inertia member 247 so that a greater or lesser number of teeth are required to pass the inertia device before tripping occurs. A further adjustment of the ratchet wheel is provided for accurately adjusting the duration of the short time delay tripping. This adjustment includes the adjusting screw 236 (Fig. 1). As previously described, the spring 229 is given an initial tension and the arm 231 of the segmental lever 233 is spaced from the arm 225 of the lever 215 by means of the spacer rod 235. Since the lever 215 is biased to its normal position, as shown in Figs. 1 and 2, by the spring 255 and toggle 265-267, it will be obvious that by turning the screw 236 the position of the segmental lever 233 may be varied relative to the position of the lever 215 in either direction depending on the direction the screw 236 is turned. The segmental lever 233 acting through the pinion 239 and sleeve 243 correspondingly moves the ratchet wheel 245 relative to the inertia device 247. The degree of movement of the ratchet wheel by adjustment of the screw 236 is relatively small to provide for vernier adjustment of the short time delay tripping. The screw 236 is locked in its adjusted position by means of a lock nut 275.

The movable core structure and the escapement time delay device are restored to their normal positions following a short time delay tripping operation by the weight of the movable core structure and spring 255 and toggle 265-267.

When an overload current of 1000% or more, or a short circuit occurs the entire movable core structure acts as a solenoid and functions to instantaneously trip the breaker. Under this circuit condition, the movable core structure operates the lever 215 (Fig. 2) but stretches the spring 229 (Fig. 1) without operating the escapement device 205. The movable core structure is restored to its normal position following an instantaneous tripping operation by the springs 255 and 229 assisted by the weight of the core structure.

The invention provides an improved trip device for a circuit breaker having a time delay means comprising a time delay element sealed in a casing containing a body of fluid for controlling the tripping operation on overload currents in the low range of overload current values, a second time delay device comprising a mechanical escapement device for controlling the tripping operation on overload currents in the intermediate range of overload current values, the trip device functioning to instantaneously trip the breaker independently of both of said time delay devices in response to overload currents.

above the intermediate range of overload currents, or on short circuits.

Having described the invention in accordance with the patent statutes, it is to be understood that various changes and modifications may be made in the structural details and combination of elements disclosed without departing from some of the essential features of the invention. It is, therefore, desired that the language of the appended claims be given as reasonably broad interpretation as the prior art permits.

We claim as our invention:

1. In a circuit breaker, a trip device comprising an energizing winding, a fixed magnet yoke having a portion of reduced cross section, a sealed casing movable to effect a tripping operation, a first armature at one end of said casing for moving said casing upon energization of said trip device by certain overload currents, a first time delay means comprising a magnetizable member disposed in said casing and having a portion of reduced cross section, means biasing said magnetizable member to a normal position wherein the portion of reduced cross section cooperates with the portion of reduced cross section of said magnet yoke to form an air gap of high density flux, said air gap restraining said magnetizable member against movement when said trip device is energized by said certain overload currents to thereby retard movement of said casing with a relatively long time delay, a second armature in axial alignment with said first armature for moving said casing upon energization of said trip device by certain other overload currents, and a second time delay means comprising a mechanical escapement device connected to said second armature operable when said trip device is energized by said certain other overload currents to retard movement of said casing with a relatively short time delay.

2. In a circuit breaker, a trip device comprising an energizing winding, a fixed magnet yoke having a portion of reduced cross section, a sealed casing movable within said magnet yoke to effect a tripping operation, a first armature at one end of said casing movable upon energization of said trip device by overload currents of certain value to move said casing, a time delay device comprising a magnetizable member disposed in said sealed casing and having a portion at one end thereof of reduced cross section, means biasing said magnetizable member to a normal position wherein said portion of reduced cross section cooperates with the portion of reduced cross section of said magnet yoke to form an air gap of high density flux, said air gap restraining said magnetizable member against movement when said trip device is energized by said overload currents of certain value to thereby retard movement of said casing with a relatively long time delay, a second armature in axial alignment with said first armature for moving said casing when said trip device is energized by overload currents of certain other value, a mechanical escapement device for retarding movement of said second armature with a relatively short time delay, a lever having one end connected to said second armature for operating said mechanical escapement device, and means permitting movement of said casing by said second armature independently of said time delay device to effect an instantaneous tripping operation.

3. In a circuit breaker, a trip device comprising an energizing winding, a fixed magnet yoke having a portion of reduced cross section, a sealed

casing movable within said magnet yoke to effect a tripping operation, a first armature at one end of said casing movable upon energization of said trip device by overload currents of certain value to move said casing, a time delay device comprising a magnetizable member disposed in said sealed casing and having a portion at one end thereof of reduced cross section, means biasing said magnetizable member to a normal position wherein said portion of reduced cross section cooperates with the portion of reduced cross section of said magnet yoke to form an air gap of high density flux, said air gap restraining said magnetizable member against movement when said trip device is energized by said overload currents of certain value to thereby retard movement of said casing with a relatively long time delay, a second armature in axial alignment with said first armature for moving said casing when said trip device is energized by overload currents of certain other value, a mechanical escapement device for retarding movement of said second armature with a relatively short time delay, a lever having one end connected to said second armature for operating said mechanical escapement device, means on said lever for engaging and moving said casing when said trip device is energized by overload currents of said certain other value, and means permitting movement of said casing by said second armature independently of said time delay device to effect an instantaneous tripping operation.

4. In a circuit breaker, an electromagnetic trip device comprising an energizing winding, a fixed magnet yoke having a portion of reduced cross section, a sealed casing movable within said winding to effect a tripping operation, a first armature at one end of said casing for moving said casing in response to certain abnormal circuit conditions in said winding, a first time delay means comprising a magnetizable member in said sealed casing biased to a normal position adjacent the other end of said casing, one end of said magnetizable member forming an air gap with said first armature and having a portion of reduced cross section cooperating with the portion of said magnet yoke to form an air gap of high density flux for restraining said magnetizable member against movement relative to said magnet yoke to thereby retard movement of said casing, a second armature movable relative to said first armature in response to certain other abnormal circuit conditions in said winding to move said casing, a second time delay device connected to said second armature for retarding movement of said second armature when said second armature is moved in response to said certain other abnormal conditions, and spring means between said first and second armatures for permitting movement of said second armature relative to said first armature when said second armature is moved in response to said certain other conditions.

5. In a circuit breaker, an electromagnetic trip device comprising an energizing winding, a fixed magnet yoke having a portion of reduced cross section, a sealed casing movable within said winding to effect a tripping operation, a first armature at one end of said casing for moving said casing in response to certain abnormal circuit conditions in said winding, a first time delay means comprising a magnetizable member in said sealed casing biased to a normal position adjacent the other end of said casing, one end of said magnetizable member forming an

air gap with said first armature and having a portion of reduced cross section cooperating with the portion of said magnet yoke to form an air gap of high density flux for restraining said magnetizable member against movement relative to said magnet yoke to thereby retard movement of said casing, a second armature movable relative to said first armature in response to certain other abnormal circuit conditions in said winding to move said casing, a second time delay device connected to said second armature for retarding movement of said second armature when said second armature is moved in response to said certain other abnormal conditions, and spring means between said first and second armatures for permitting movement of said second armature relative to said first armature when said second armature is moved in response to said certain other conditions, and means for adjusting the tension of said spring to vary the minimum abnormal condition required to move said second armature relative to said first armature.

6. In a circuit breaker, an electromagnetic trip device comprising an energizing winding, a fixed U-shaped magnet yoke, a sealed casing movable within said winding to cause a tripping operation of said trip device, a first armature disposed at one end of said casing for moving said casing upon energization of said trip device by certain overload currents below a predetermined value, a first time delay device comprising a magnetizable member disposed in said sealed casing and biased to the other end of said casing to form an air gap with said magnet yoke, said air gap restraining said magnetizable member against movement when said trip device is energized by said certain overload currents to retard movement of said casing with a relatively long time delay, a second armature disposed outside said casing and movable within said winding for moving said casing upon energization of said trip device by certain other overload currents below said predetermined value, a second time delay device comprising a mechanical escapement operatively connected to said second armature and operable when said trip device is energized by said certain other overload currents to retard movement of said casing with a relatively short time delay, a spring between said first and second armatures permitting movement of said second armature relative to said first armature to reduce the air gap therebetween when said second armature is moved in response to said certain other overload currents below said predetermined value, and a spring between said second time delay device and said second armature to permit movement of said casing by said second armature independently of both of said time delay devices to thereby effect instantaneous operation of said trip device.

7. In a circuit breaker, an electromagnetic trip device comprising an energizing winding, a fixed magnet yoke, a sealed casing movable within said winding to cause a tripping operation, a first armature disposed at one end of said casing for moving said casing upon energization of said trip device by overload currents of certain value, a magnetizable member disposed in said sealed casing and biased to the other end of said casing to form an air gap with said magnet yoke whereby said magnetizable member is restrained against movement when said trip device is energized by said overload currents of a certain value to retard movement of said casing with a relatively long time delay, a tubular armature movable within said winding for moving said

sealed casing upon energization of said trip device by overload currents of a certain other value, a mechanical escapement device operatively connected to said tubular armature and operable when said trip device is energized by overload currents of said other value to retard movement of said tubular armature with a relatively short time delay, a spring in said tubular armature disposed between said first armature and said tubular armature for permitting movement of said tubular armature relative to said first armature when said tubular armature is moved in response to said overload current of certain other value, and adjusting means for adjusting the tension of said spring to vary the minimum overload current required to move said tubular armature relative to said first armature.

8. In a circuit breaker, an electromagnetic trip device comprising an energizing winding, a magnet yoke, a sealed casing movable within said winding to cause a tripping operation of said device, a first armature at one end of said casing for moving said casing upon energization of said trip device by certain overload currents below a predetermined value, a first time delay device comprising a magnetizable member in said casing biased to the other end of said casing to form an air gap with said magnet yoke, said magnetizable member being held against movement by energization of the trip device by said certain overload currents to retard movement of said casing, a second armature also movable within said winding for moving said casing upon energization of said trip device by certain other overload currents below said predetermined value, a spring between said first and second armatures permitting movement of said second armature relative to said first armature, a second time delay device for retarding movement of said second armature, a lever having one end connected to said second armature for operating said second time delay device, and a spring between said second time delay device and said lever permitting movement of said casing by said second armature independently of both of said time delay devices to effect an instantaneous tripping operation upon energization of said trip device by overload currents above said predetermined value.

9. In a circuit breaker, an electromagnetic trip device comprising an energizing winding, a magnet yoke, a sealed casing movable within said winding to cause a tripping operation, a first armature at one end of said casing for moving said casing upon energization of said trip device by certain overload currents below a predetermined value, a first time delay device comprising a magnetizable member in said casing biased to one end of said casing to form an air gap with said magnet yoke, said magnetizable member being held against movement by energization of said trip device by said certain overload currents to retard movement of said casing, a second armature also movable within said winding for moving said casing upon energization of said trip device by certain other overload currents below said predetermined value, a spring between said first and second armatures permitting movement of said second armature relative to said first armature, a second time delay device comprising a mechanical escapement for retarding movement of said second armature, a lever operable by said second armature for operating said mechanical escapement, and a spring between said lever and said mechanical escapement permit-

ting movement of said casing by said second armature independently of said first and second time delay devices to effect an instantaneous tripping operation upon energization of said trip device by overload currents above said predetermined value.
